UNITED STATES PATENT OFFICE.

FRANK E. SHAILOR, OF PITTSFIELD, MASSACHUSETTS, ASSIGNOR TO GENERAL ELECTRIC COMPANY, A CORPORATION OF NEW YORK.

ELECTRIC FLAT-IRON.

1,102,300.

Specification of Letters Patent.

Patented July 7, 1914.

Application filed April 19, 1913. Serial No. 762,217.

To all whom it may concern:

Be it known that I, FRANK E. SHAILOR, a citizen of the United States, residing at Pittsfield, county of Berkshire, State of Massachusetts, have invented certain new and useful Improvements in Electric Flat-Irons, of which the following is a specification.

My invention relates to electric flat-irons and more particularly to means for controlling the supply of electric energy thereto. It is common to provide the flat-iron merely with a detachable connection plug for this purpose. A plug of this kind has the advantage that it is simple and will stand very rough usage. However it is inconvenient to detach the plug from the iron every time that it is desired to cut off the current and to replace it when it is desired to reestablish the supply. Various switch devices attached to the plug have been devised but to these the common objection is applicable that they are very easily put out of order if not handled very carefully and also by the repeated operation thereof. The object of my invention is to provide a rugged and efficient switch for a flat-iron which may be quickly and conveniently operated and so will not be open to the above stated objections.

According to my invention a switching member is mounted on the flat-iron adjacent to terminals connected to the electric heating unit. The said switching member carries contacts and is mounted to swing around a pivot and so to bring the said contacts into or out of engagement with the aforesaid terminal connections of the heating unit. I prefer that the switching member shall be in the form of a plug and that it shall be so mounted that it may be entirely removed from the flat-iron whenever desired.

Although not essential to my invention I prefer that the switch plug shall be vertically pivoted and mounted close to the handle of the flat-iron as this renders it very convenient to manipulate. In order that the construction may be as compact as possible I prefer to attach to the rear of the flat-iron a vertically disposed stand in such position that the flat-iron when tipped on end will be supported by said stand clear of the table or board and to mount the switch plug upon the upper attaching support of said stand.

In order that the plug may not become accidentally detached I provide means whereby such detachment is prevented except in certain positions of the said plug.

Various other features and advantages of my invention will appear from the detailed description which follows.

My invention will be more clearly understood by referring to the accompanying drawing in which—

Figure 1 is a perspective view of a flat-iron equipped with my invention and showing the switch plug detached from the iron; Fig. 2 is a partial vertical section through the flat-iron with the switch plug in its closed circuit position and Fig. 3 is a top plan view of the switch plug and stand with the adjacent portions of the flat-iron when the switch is in open circuit position.

As shown in the drawing the flat-iron has the body portion 10 comprising the base 11 between which and the clamping plate 12 is held the electric resistance heating unit 13 which may be such as that disclosed in Parkhurst Patent No. 953,393. The leads 14 and 15 from the said unit are carried up through an aperture in the top casing 16 of the iron and attached by screws 17 to the conductor strips 18 and 19 respectively. The said strips are supported in position between the handle support 20 from which they are insulated by a sheet of mica 21 and the insulation block 22 of porcelain or similar material. A metal casing 23 surrounds the said parts and is held with them in place by the screw 24. Terminals 25 and 26 are in electrical contact with the said strips and extend at right angles thereto through slots in the block 22. The portion of the said block adjacent to said terminals is uncovered. Screws 27 serve to hold this portion of the block and terminals rigidly in place against the handle support 20.

A stand having the normally vertically extending base 28 and horizontally extending plates 29 and 30 is attached to the body portion of the flat iron by screws 31 and to the handle support by screw 32 extending through the vertical channel member 33. The plate 30 has a vertical pivot pin 34 extending upwardly therefrom.

The switch plug 35 consists of an insulating block of porcelain or similar material which is apertured to receive the spring terminal sockets 36 attached to plates 37 and 38.

electrically connected through terminal screws 38 to the conductors 39. The said conductors extend to an external circuit through an aperture in the side of the block 5 with which registers the sleeve 40 which may be integral with the metal casing 41 of the switch plug. The said casing and block have an aperture 42 in the bottom thereof to receive the pivot pin 34. The bottom of 10 the switch plug also has a depression there-in adapted to receive the pin 43 which projects through the plate 30 and is carried by the spring plate 44 attached to the under side of the said plate by screw 45. The bottom of the casing 41 has lugs 46 and 47 projecting therefrom. These are adapted 15 to enter slots 48 and 49 respectively in the block 22 and channel 33 when the switch plug is in closed circuit position.

20 The handle of the iron is represented by the reference numeral 50.

From the foregoing description it will be apparent that the switch plug may be readily placed in position over the pivot pin 34 25 by holding it in such position that the lug 46 is entirely without the slot 48. The plug may then be turned into closed circuit position in which the sockets 36 engage the terminal pins 25 and 26. If it is desired to 30 open the circuit without detaching the plug, the latter may be swung to the position shown in Fig. 3 by merely sliding the hand rearwardly against the projecting sleeve 40. In this and the closed circuit position the engagement of lug 46 with slot 48 effectively 35 prevents the accidental removal of the plug. At any time the flat-iron may be tilted on end so as to be supported by the stand 28. If it is desired to remove the switch plug, 40 this may be done very easily by turning it until lug 46 clears the slot 48 and then raising it vertically.

The above described structure furnishes a 45 very compact and convenient means for operating the electrical connections of a flat-iron and one which should not easily be put out of order. Various modifications thereof will readily occur to those skilled in the art and are to be considered as coming within 50 the scope of my invention as set forth in the following claims.

What I claim as new and desire to secure by Letters Patent of the United States, is:—

1. The combination with an electrically 55 heated flat-iron having fixed terminal contacts, of a vertically pivoted switch plug mounted upon said iron and carrying contacts adapted to engage said terminal contacts.

60 2. The combination with an electrically heated flat-iron having fixed terminal contacts, of a vertically pivoted removable switch plug supported by said iron and carrying contacts adapted to engage said terminal contacts.

3. The combination of an electrically heated flat-iron having contact terminals at the rear thereof and a switch plug freely pivoted adjacent said terminals and carrying contacts arranged to engage said terminals, whereby the switch plug is adapted to be manually operated to bring the contacts of the switch plug into or out of engagement with said terminals. 70

4. The combination of an electrically heated flat-iron having contact terminals mounted at the rear thereof and a switch plug pivotally supported adjacent said terminals and freely removable from the pivot in a given position with reference to the 80 terminals and adapted in its movement to bring the contacts carried thereby into and out of engagement with the terminals, and means for preventing the removal of said switch from the pivot in closed circuit position. 85

5. The combination with an electrically heated flat-iron having contact terminals located at the rear of said flat-iron, a handle for said flat-iron and supports therefor, a 90 supporting member attached to the rear handle support and a switching member pivotally supported thereby, said switching member carrying contacts adapted to engage with said terminal in one position of 95 the said switching member.

6. The combination with an electrically heated flat-iron having contact terminals located at the rear of said flat-iron, a handle for said flat-iron having supports, a supporting member attached to the rear handle support and a switching member pivotally and removably supported thereby, said switching member carrying contacts adapted to engage the said terminals in one position of the said switching member, and means for preventing the removal of the said member in certain positions of the same. 100

7. The combination with an electrically heated flat-iron having contact terminals mounted at the rear of said flat-iron, a handle for said flat-iron having supports, a horizontally disposed supporting member attached to the rear handle support of the said flat-iron, a substantially vertically extending pivot projecting upwardly from said member, and a switch plug engaging said pivot and adapted to turn about the same, said switch plug carrying contacts arranged to engage with said terminals in 110 one position of the same. 115

8. The combination with an electrically heated flat-iron having terminal contacts located at the rear of said flat-iron, a stand having substantially vertically extending 125 base and a horizontally disposed supporting plate attached to the said flat-iron, and a switch plug carrying contacts pivotally mounted upon said plate, and adapted to be turned so as to bring its contacts into or 130

out of engagement with the said terminal contacts.

9. The combination with an electrically heated flat-iron having terminal contacts located at the rear of the said flat-iron, a stand having a substantially vertical extending base and a substantially horizontally disposed supporting plate therefor attached to the said flat-iron and a removable switch plug carrying contacts pivotally mounted upon the said plate and adapted to be turned so as to bring its contacts into or out of engagement with the said terminal contacts.

10. The combination with an electrically heated flat-iron having terminal contacts located at the rear of the said flat-iron, a stand

having a substantially vertical extending base and a horizontally disposed supporting plate therefor attached to the said flat-iron 20 and a removable switch plug carrying contacts pivotally mounted upon the said plate and adapted to be turned so as to bring its contacts into or out of engagement with the said terminal contacts, and means for preventing the removal of the switch plug when in certain positions.

In witness whereof, I have hereunto set my hand this 17th day of April, 1913.

FRANK E. SHAILOR.
